[57] CLAIM

The ornamental design for a combined pen and flashlight, as shown and described.

DESCRIPTION

FIG. 1 is a front elevational view of a combined pen and flashlight showing my new design in an exploded condition;

FIG. 2 is a rear elevational view in an exploded condition, shown partially broken away for convenience of illustration;

FIG. 3 is a left side elevational view of FIG. 2;

FIG. 4 is a right side elevational view of FIG. 2;

FIG. 5 is a top plan view of FIG. 1; and

FIG. 6 is a bottom plan view of FIG. 1.
